CLAIM

The ornamental design for a magazine release catch for a pistol, as shown and described.

DESCRIPTION

FIG. 1 is a right side elevation of a preferred embodiment of the magazine release catch for a pistol showing our new design.

FIG. 2 is a left side elevational view thereof.

FIG. 3 is a front elevational view thereof.

FIG. 4 is a rear elevational view thereof.

FIG. 5 is a top plan view thereof.

FIG. 6 is a bottom plan view thereof; and,

FIG. 7 is a perspective view thereof, as seen from the right. Parts of the pistol shown in broken lines in FIGS. 1-7 do not form part of our design.
